UNITED STATES PATENT OFFICE.

ROBERT E. EINSTEIN, OF ST. LOUIS, MISSOURI, ASSIGNOR TO VAUGHN RAIL SUPPORT COMPANY, OF ST. LOUIS, MISSOURI, A CORPORATION OF ILLINOIS.

RAIL-CHAIR.

1,358,066.

Specification of Letters Patent.

Patented Nov. 9, 1920.

Application filed March 29, 1920. Serial No. 369,731.

To all whom it may concern:

Be it known that I, ROBERT E. EINSTEIN, a citizen of the United States, residing at St. Louis, Missouri, have invented a certain 5 new and useful Improvement in Rail-Chairs, of which the following is a full, clear, and exact description, such as will enable others skilled in the art to which it appertains to make and use the same.

10 This invention relates to rail chairs, namely, devices of the kind that are used for supporting a rail in an elevated position above a track tie.

The object of my invention is to provide 15 a strong and rigid one-piece rail chair that is inexpensive to manufacture and of such design that a rail can be securely connected to same by bending portions of the chair into engagement with the base flange of the 20 rail.

To this end I have devised a rail chair 25 that comprises a horizontal web on which the base flange of the rail rests, a pair of vertical walls carrying said web and extending the entire length of the chair, and rail holding portions integrally connected to said vertical walls and formed by portions that are severed from said horizontal web. The chair is provided with horizontally-disposed 30 flanges which rest upon the track tie that supports the chair and gussets are preferably arranged at the junction of said flanges and the vertical walls of the chair so as to reinforce and strengthen said walls.

35 Figure 1 of the drawings is a perspective view of a rail chair constructed in accordance with my invention; and

Fig. 2 is a similar view, showing how the rail holding portions are adapted to be bent 40 downwardly into engagement with the base flange of the rail supported by the chair.

Referring to the drawings which illustrate a rail chair constructed in accordance 45 with my invention and formed from a sheet of metal that is forged or pressed into shape, A designates the horizontally-disposed web of the chair on which the base flange of the rail rests, B designates a pair of parallel, vertical walls that extend longitudinally of the rail and carry said web and C designates 50 horizontally-disposed flanges that project laterally from the lower ends of said walls B so as to form a wide, substantial bearing surface for the chair on the track tie to which 55 the chair is connected, said flanges having

holes 1 in same through which fastening devices can be driven into the tie. The chair is equipped with rail holding portions 2 that are integrally connected to the vertical walls B and which are formed preferably by severing portions of the horizontal web A and bending said severed portions upwardly, as shown in Fig. 1. After the rail has been arranged in operative position on the chair, with the base flange of the rail supported 60 on the web A, the rail holding portions 2 are bent inwardly and downwardly over the base flange of the rail into the position shown in Fig. 2, thus securely connecting the rail 65 to the chair. The parts 3 of the web A that lie between the severed portions 2 are retained so as to form extensions at the ends of the web A that provide additional bearing surfaces for the base flange of the rail supported by the chair. If desired, gussets 70 4 may be provided at the intersection of the vertical walls B and the tie engaging flanges C so as to reinforce and strengthen said 75 walls.

A rail chair of the construction above described can be manufactured at a low cost, as it can be formed from a sheet of metal forged or pressed into the shape shown. A rail can be attached to the chair quickly and easily by simply bending the portions 2 inwardly and downwardly into engagement with the base flange of the rail and such a chair is exceptionally strong and rigid, owing to the fact that it is provided with reinforced vertical walls B that extend through- 80 out the entire length of the chair. The horizontal web A forms a wide substantial bearing for the base flange of the rail, and as said base flange is gripped securely at four points by the rail holding portions 2, there 85 is little liability of the rail pulling loose 90 from the chair.

Having thus described my invention, what I claim as new and desire to secure by Letters Patent, is:

1. A rail chair provided with a pair of parallel, vertical walls that extend longitudinally of the rail, tie engaging flanges 100 projecting laterally from the lower edges of said walls, a horizontally-disposed web 105 connected to said walls for supporting the base flanges of the rails and provided at its ends with extensions that lie in the same horizontal plane as said web, and oppositely-disposed rail holding portions integrally con- 110

nected to said vertical walls and adapted to be bent into engagement with the base flanges of the rails, said rail holding portions being arranged in transverse alinement with 5 said extensions.

2. A rail chair provided with tie engaging portions, a rail supporting portion arranged in a higher horizontal plane than said tie engaging portions and consisting of a horizontally-disposed web, vertical walls that carry said web and connect it to said tie engaging portions, and a pair of integral rail holding portions at each end of said web that are adapted to be bent inwardly and down- 10 wardly into engagement with the base flanges of the rails, each of said pairs of rail holding portions being formed by cutting two parallel slits in the end part of the web 15

and then bending said severed sections upwardly at an angle to said web. 20

3. A one-piece rail chair, comprising a horizontally-disposed web integrally connected to a pair of parallel, vertical walls that extend longitudinally of the rails, integral tie engaging flanges projecting laterally from the lower edges of said vertical walls, oppositely-disposed rail holding portions projecting upwardly from said vertical walls at the ends of said web, integral extensions on the ends of said web that lie underneath the sections of the base flanges of the rails on which said rail holding portions bear, and gussets arranged at the intersection of said vertical walls and tie engaging flanges. 25 30
